(57) **CLAIM**

The ornamental design for a shaving razor handle as shown and described.

DESCRIPTION

FIG. 1 is a front perspective view of a shaving razor handle; FIG. 2 is a top view thereof; FIG. 3 is a bottom view thereof; FIG. 4 is a right side view thereof; FIG. 5 is a left side view thereof; FIG. 6 is a front view thereof; FIG. 7 is a back view thereof; and, FIG. 8 is rear perspective view thereof.

The broken lines shown illustrate portions of the shaving razor and form no part of the claimed design.
